UNITED STATES PATENT OFFICE

149,407

DESIGN FOR A ROUNDABOUT

James S. Evans, San Marino, Calif.

Application April 18, 1946, Serial No. 128,723

Term of patent 14 years

(Cl. D34—5)

To all whom it may concern:

Be it known that I, James S. Evans, a citizen of the United States of America, residing at San Marino, in the county of Los Angeles and State of California, have invented a new, original, and ornamental Design for a Roundabout, of which the following is a specification, reference being had to the accompanying drawing, forming a part thereof, wherein:

Fig. 1 is a top-plan view of a roundabout showing my new design; and

Fig. 2 is a side elevational view of the roundabout shown in Fig. 1.

I claim:

The ornamental design for a roundabout, as shown.

JAMES S. EVANS.
